(57) **CLAIM**

The ornamental design for a light fixture as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front, top, right perspective view of a first embodiment of a light fixture showing my new design; FIG. 2 is a rear, bottom, left perspective view thereof; FIG. 3 is a front elevation view thereof; FIG. 4 is a rear elevation view thereof; FIG. 5 is a right side elevation view thereof; FIG. 6 is a top plan view thereof; FIG. 7 is a bottom plan view thereof; FIG. 8 is a front, top, right perspective view of a second embodiment of a light fixture showing my new design; FIG. 9 is a rear, bottom, left perspective view thereof; FIG. 10 is a front elevation view thereof; FIG. 11 is a rear elevation view thereof; FIG. 12 is a right side elevation view thereof; FIG. 13 is a top plan view thereof; and, FIG. 14 is a bottom plan view thereof.

The broken lines in the figures illustrate portions of the light fixture that form no part of the claimed design.

1 Claim, 14 Drawing Sheets
